SNAP FRONT HANDBAG

Abraham Schocket, Bronx, N. Y.

Application December 28, 1948, Serial No. 67,629

4 Claims. (Cl. 150—34)

1

This invention relates to new and useful improvements in handbags, and, more particularly, the aim is to provide a novel and valuable handbag, as for ladies' use, incorporating, among other advantages, a swingably mounted structure for carrying one or more removable articles, as articles falling in the class typified by cosmetics, combs, nail files, coin purses, mirrors, memorandum pads and booklets, pens, pencils, etc., etc.

The new handbag may have a handle constituting an over-the-shoulder strap, or any other type of handle, and the new handbag may be of the envelope type, a pouch bag with a closing frame, or otherwise; and the swingably mounted structure above-mentioned may be on the inside or outside of the bag. While various handbags are herein shown having variously included single swinging structures, within the invention there may be a plurality of such structures, with either or both on the inside or the outside of the bag.

A further feature of the invention involves the provision of a snap-front bag with end gussets, this bag preferably of the envelope type, and with snap-fastener type securing means some of the elements of which are carried by inturned front terminal portions of said gussets and some others of which are carried by the inner side of a swingably mounted structure which is at the outside of the bag. This handbag, preferably, has a top closing flap, with one or more fastening elements on said flap and one or more complementary fastening elements on the outside of or extended through said swingably mounted structure.

In a handbag having end gussets according to the invention, a further feature is the provision of a partition dividing the bag to provide at least one main compartment, with a single gusset at each end of the bag and with each of such gussets connected at an intermediate line along its heightwise dimension to the opposite ends of said partition.

The fitments in the bag, to be detachably secured thereto or to be slidably pocketed therein, may vary widely, and the pockets and compartments in the bag, as to number, size and arrangement (as, for instance, on one or both sides of a swingably or non-swingably mounted wall structure), may also vary widely.

For further comprehension of the invention, and of the objects and advantages thereof, reference will be had to the following description and accompanying drawings, and to the appended claims in which the various novel fea-

tures of the invention are more particularly set forth.

In the accompanying drawings forming a material part of this disclosure:

5 Fig. 1 is a perspective view, showing one now favored embodiment of the invention, closed, and disposed as though suspended for carrying from a handle fragmentarily shown and which may be an over-the-shoulder strap.

10 Fig. 2 is also a view in perspective, but one drawn to an enlarged scale; this showing the bag of Fig. 1 opened up at its top flap and at its exterior swinging structure.

15 Fig. 3 is a further enlarged detail view, this being a section taken on the line 3—3 of Fig. 2.

Fig. 4 front elevationally fragmentarily shows the bag as opened in Fig. 2, but with the fitment next-mentioned assumed removed and hence here merely indicated in dot and dash lines.

20 Fig. 5 is an elevational view of the fitment constituting a coin purse as shown in full lines in Fig. 2, but looking at the side of said purse which is remote from the observer of Fig. 2.

Fig. 6 is a view similar to Fig. 2, but showing another now favored embodiment of the invention.

25 Fig. 7 is an enlarged vertical section, taken on the line 7—7 of Fig. 6.

Fig. 8 is a perspective view, showing a modified fitment, of composite utility, as for removable storage in and for combination with the handbag of Figs. 6 and 7, and, for further example, as for having a portion thereof nested in the handbag in a manner analogous to that illustrated in Fig.

30 7 in connection with a portion of the fitment of Figs. 6 and 7 constituting a memorandum book with attached pencil.

Fig. 9 is a view similar to Figs. 2 and 6, but showing still another now favored embodiment 40 of the invention; this bag being exemplary of one having an interior swingably mounted structure.

Fig. 10 is a rear elevation of said structure, that is, looking toward the side thereof remote from the observer of Fig. 9, and with the main parts of the pivotal mounts for said structure also shown but out of connection with the main body of the bag.

45 Fig. 11 is an enlarged detail view, this being a section taken on the line 11—11 of Fig. 10, and with merely the main plies of the adjacent wall structure indicated in dot and dash lines.

Referring now to the drawings more in detail, and first to Figs. 1-5, the handbag here illustratively shown is as a whole marked 20; the same

including wall structures providing a closing flap 21 (this incorporating a top panel portion 22 and a flap-proper portion 23), a back wall 24 and a bottom wall 25. Two like but reversely arranged side gussets 26 and 27 are also included in the bag structure. A description in detail of the gusset 26, therefore, will suffice as a description of both.

Said gusset 26, longitudinally thereof, that is, in a direction height-wisely of the main bag body, is marginally secured, as by a stitching 28, to the back or rear wall 24; and also, as by a continuation 29 of the stitching 28, this gusset is attached along its bottom to the adjacent end edge of the bottom wall 25. Intermediate its width and along a line height-wisely thereof the gusset 26 is folded to provide a troughing 30, and inserted into the latter is an end of a partition 31, and said end of the partition is there secured in place by a stitching 32. The opposite end of said partition 31 is similarly attached to a matching troughing of the gusset 27; and the bottom edge of the partition is suitably secured to the remainder of the main body of the bag.

Forward of the troughing 30 and substantially parallel with the latter the gusset 26 has another troughing 33, and a narrow panel-like terminal portion of said gusset forward of said troughing 33 is folded in to provide a two-ply structure which may aptly be called a flexible post 35; the free edge of said terminal portion being sent into the troughing 33 and being there secured by a stitching 34. The posts 35 thus established at the forward ends of the gussets 26 and 27 may have their lower ends free, or said posts 35 may be suitably secured at their bottom ends, as by cutting each gusset so that the lower end portion of its said post may be forwardly bent for tucking in between the main structure of a swingably mounted front wall 36 and an auxiliary inner wall element 37 stitched in place as shown in Fig. 2 to said front wall 36.

At its front side and near its upper end each of said posts carries the socket element 38 of a snap fastener the complementary element for each of which is a post snap fastener element 39 mounted on the inner side of the front wall 36. Thus, after the flap 21 is opened, the said wall 36 may be readily swung open, and, preparatory to closing said flap and locking or latching it in a manner to be explained, the said wall 36 may be closed and secured closed by snapping together the fastener elements 38 and 39.

Reverting to said auxiliary wall element 37, the stitchings connecting the same to the front wall 36 include several stitchings 40 all extending laterally of this wall 37, thereby to provide a line of pockets adapted to be used, as shown in Fig. 2, for detachably holding a mirror 41, a comb 42, a lipstick 43, and another article such as indicated at 44.

A detachably included structural component of the handbag is a coin purse 45; said purse carrying at its rear side a post type snap fastener element 47. The complementary socket element 46 of said fastener is carried at the forward side of the partition 31. The purse can be readily detached; but normally it will be mounted on the partition 31 as shown in Fig. 2, for accommodation of the entirety or the main portion of its thickness in the space provided between the posts at the front ends of the gussets 26 and 27, and in a manner not to interfere with ready opening and closing of the purse or with the ready withdrawal of part or all of its contents when desired.

Between the back wall 24 and the partition 31 is provided a main compartment 48 of an expanse substantially the same as that of the rear wall 24.

The means for locking or latching the flap 21 in bag closing position as in Fig. 1 is shown as including a grommetted or suitably reinforced opening 50 through the flap proper 23 and a device 49 fixed on the front wall 36 which constitutes in this form of the invention an example of a swingably mounted structure at the exterior of the bag. Said device 49 is of a familiar type incorporating a basal portion from which projects an elongate head associated with inbuilt impositive detent means whereby when the head is turned through a quarter revolution it snaps into retention of its thus reset position; and the opening 50 is also elongated, so that, as shown in Fig. 1, with said head arranged to extend at right angles to the length of said opening, the lock or latch desired is effectuated.

The panel like portion 22 of the flap 21 has extended from its opposite ends a pair of like loops 51, each of these connected to one of the two handle ends 52.

Referring to the embodiment illustrated in Figs. 6 and 7, the parts here shown and to which have been applied reference numerals with primes added correspond, respectively, to the parts of Figs. 1-5 to which have been applied the same reference numerals but without primes.

The wall element 37' is shown as somewhat wider than the wall element 37, and is stitched merely along three of its four sides, to provide a compartment 53 having an open mouth adjacent to the swinging end of the front wall 36'. Such compartment may be used, as here shown, for keeping in place in the bag, and between uses, such an article as the loose-leaf memorandum or note book marked 54, said book having a projected loop 55, for detachably holding a pencil 56.

The partition 31' has secured thereto, as by the stitching indicated, a minor auxiliary partition 57, the latter having a central opening as shown and so to provide a framing around a mirror 58 insertable into and withdrawable from the pocket provided between these two partitions, such pocket being open at its top. As shown at 59, a comb or the like may be held in a pocket of downwardly diminishing thickness provided between the rear of such mirror and the front side of the partition 31'.

The panel like portions 22' of the flap 21' has extended from its opposite ends a pair of like loops 60, these having their bights extended parallel with the general plane of said panel like portion 22'. Engaged with each such loop is a substantially square eye 61, and each such eye also is engaged with a looped end portion 62 of the handle.

In Fig. 7, the head 49' is shown in two of its positions, the delineation in full lines being its locking position, and the delineation in broken lines being its release position.

Referring to the showing of Fig. 8, this is illustrative of a detached or detachable yet basic component of the main structure of the handbag body, which may be used in combination with the bag of Fig. 2, and, with particular facility, in connection with the bag of Fig. 6. The structure of Fig. 8 may aptly be called an insert component of the handbag. This insert as a whole is designated 63, and the same includes an inner wall 63' and an outer wall 64. Each of these walls when cut is substantially an elongated rectangle, and they are stitched together as indicated along their opposite

sides. About half way along its length the insert 63 is folded along a line 66, and stitched adjacent to such line as indicated at 67. The portion which in Fig. 8 is at the near side of the insert 63 is open mouthed across the insert at the end of said portion remote from said fold line, to provide a compartment closed at its bottom as well as at both sides.

The walls 63^a and 64 at their ends remote from said mouth are pouched as at 68, and there provided with the conventional opening and closing frame and snap closure indicated at 69; thereby providing a coin purse. Inside said purse is a minor partition 70, the top limit of which is indicated by the broken line 71, said partition 70 being suitably secured all around the same to the wall 63^a. This wall 63^a, just below the top of the partition 70, is slotted, and here there is provided a slide fastener 72. The portion of the wall 64 which provides the last-named compartment is cut away to present an opening framed all around, and for exposing therethrough a mirror 73 detachably contained in said compartment.

The wall 63^a at the purse portion of the insert 63 carries a socket type element 74 of a snap fastener, and said wall 63^a at the mirror carrying portion of said insert carries, matchingly placed, the complementary post type element of said fastener. The portion of the wall 63^a hidden in Fig. 8 may be slotted or otherwise equipped or constructed as will be explained in connection with Figs. 9-11 and with particular reference to Fig. 10, to adapt said portion of said wall 63^a to carry additional articles even with the insert 63 folded and with its snap fastener coupled to force the said insert to little thickness even when thus folded and secured as folded.

For carrying the insert 63 in the handbag merely as an unattached insert, the snap fastener 74-75 will be used. However, as already mentioned, the insert 63 or an equivalent could well be used with such a bag as that shown in Figs. 6 and 7, and with the mirror-containing portion of said insert slid into the compartment 53, where such insert is desired to be carried in lieu of the book 54. Or, said insert 63 or an equivalent could be used, in an analogous manner, with such a bag as is shown in Figs. 9-11, in connection with the compartment provided below the wall element 37" of Fig. 9.

Referring to the embodiment illustrated in Figs. 9-11, the parts here shown and to which have been applied reference numerals with double primes added correspond, respectively, to the parts of Figs. 1-5 to which have been applied the same reference characters without primes or to the parts of Figs. 6 and 7 to which have been applied the same reference characters without primes.

The last referred-to compartment, this designated 76, is provided between the front wall 36", and the inner wall element 37" for said front wall; it being noted that said wall element 37" is like the wall element 37' of Fig. 6, rather than like the wall element 37 of Fig. 2 stitched at 40 to provide a line of small compartments. In other words, a single large compartment 76 is present here; so that, as just above stated, the insert 63 of Fig. 8 may be used therewith as explained, or the memorandum book 54 or an equivalent may be so used.

In back of the partition 31" is an extra partition 77, thereby to provide, in front of the main compartment 48", a second main compartment of substantially equal expanse; the latter closable 75

by a slide fastener 78 having its lock-lug carrying tapes attached to the top margins of the two partitions 31" and 77.

Just below the slide fastener 78 a strip 79 of suitable material is attached longitudinally thereof by the stitching indicated to the forward side of the partition 31". This strip may have its upper and lower edges rolled in behind the same to provide a buffer medium for the swinging end of a swingably mounted interior structure to be mentioned in a moment. As said strip is shown, it is also attached intermediate its ends to the partition 31" by a cross stitching 80, thereby to provide two loops one alongside the other for the reception of articles desired to be detachably there inserted.

The embodiment now being described has not only an exterior swingably mounted structure, this the front wall 36", but also an interior swingably mounted structure, this the one above mentioned in describing the buffer provided by the strip 79.

This interior swingably mounted structure, as a whole designated 81, incorporates a front wall 82 and a rear wall 83, the former having an opening 84 for framing a mirror 85 in the compartment provided between the two walls. The rear wall 83 has cut therethrough a pair of slits 86, by the aid of which a comb 87 may be detachably carried as shown. Said rear wall also has another pair of slits 88, by the aid of which a nail file 89 may be detachably carried as shown.

Said swing structure 81 may be hingedly mounted in any suitable way, but as here shown the same is thus mounted on the front wall 36" by two like pivotal supports; each of which comprises a main stamping 90 having forkedly related extensions 91, and an auxiliary stamping 92; these stampings coupled by a rivet 93 going through the structure 81 adjacent to the bottom stretch of the stitching shown and which goes around three of the four sides of said structure. These extensions or ears 91 are alignedly apertured, for the reception of a rivet to constitute a pintle 94. Also apertured for receiving this pintle is the ball head 95 of a device 96. Each such device has a recess for having forced tight therewith the shank portion of a headed wedge pin 97, which shank is sent through an aperture in the front wall 36" after being sent through an interposed washer 98 as shown in Fig. 11.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A handbag body comprising a sheet of relatively stiff material providing a rear wall and a front wall spaced by a bottom wall, said front and rear walls being integral with said bottom wall, laterally spaced gussets secured along their rear and bottom edges to the side edges of said rear and bottom walls, vertically extended plural-ply post-like members continuing from the front edges of said gussets and extended laterally inward to have their widths extend parallel to the plane of said rear wall, and means releasably securing the top outer corners of said front wall to the top ends of said post-like members.

2. A handbag body comprising a sheet of rela-

tively stiff material providing a rear wall and a front wall spaced by a bottom wall, said front and rear walls being integral with said bottom wall, laterally spaced gussets secured along their rear and bottom edges to the side edges of said rear and bottom walls, vertically extended plural-ply post-like members continuing from the front edges of said gussets and extended laterally inward to have their widths extend parallel to the plane of said rear wall, and means releasably securing the top outer corners of said front wall to the top ends of said post-like members, said post-like members being secured at their bottom ends to said sheet of material at the junction of said front wall and said bottom wall.

3. A handbag body comprising a sheet of relatively stiff material providing a rear wall and a front wall spaced by a bottom wall, said front and rear walls being integral with said bottom wall, laterally spaced gussets secured along their rear and bottom edges to the side edges of said rear and bottom walls, vertically extending plural-ply post-like members continuing from the front edges of said gussets and extended laterally inward to have their widths extend parallel to the plane of said rear wall, and means releasably securing the top outer corners of said front wall to the top ends of said post-like members, said securing means comprising snap fastener elements.

4. A handbag body comprising a sheet of relatively stiff material providing a rear wall and a front wall spaced by a bottom wall, said front and rear walls being integral with said bottom wall, laterally spaced gussets secured along their rear and bottom edges to the side edges of said rear and bottom walls, vertically extending plural-ply post-like members continuing from the front edges of said gussets and extended laterally inward to have their widths extend parallel to the plane of said rear wall, and means releasably securing the top outer corners of said front wall to the top ends of said post-like members, said securing means comprising snap fastener elements, and including an auxiliary wall element stitched to the inner face of said front wall to form therewith a plurality of article-receiving pockets.

on the inner face of said front wall at the top corners thereof and complementary snap fastener elements on the outer faces of said post-like members at the top ends thereof.

5. A handbag body, as set forth in claim 1, and including an auxiliary wall element stitched to the inner face of said front wall to form therewith a plurality of article-receiving pockets.

ABRAHAM SCHOCKET.
